UNITED STATES PATENT OFFICE

130,116

DESIGN FOR A RIMLESS SPECTACLE

Joseph J. Carlson, New York, N. Y.

Application April 21, 1941, Serial No. 100,547

Term of patent 14 years

To all whom it may concern:

Be it known that I, Joseph J. Carlson, a citizen of the United States, residing at No. 1024 Montgomery Street, in the Borough of Brooklyn, county of Kings, city and State of New York, have invented a new, original, and ornamental Design for a Rimless Spectacle, of which the following is a specification, reference being had to the accompanying drawing, forming part thereof.

In the drawing:

Fig. 1 is a top plan view of a rimless spectacle showing my new design; and

Figs. 2 and 3 are, respectively, a front view and a rear view with the temples omitted for convenience of illustration.

I claim:

The ornamental design for a rimless spectacle, as shown and described.

JOSEPH J. CARLSON.
